US0D1057512S

(12) **United States Design Patent** (10) Patent No.: **US D1,057,512 S**
(45) Date of Patent: ** Jan. 14, 2025

(54) **HAND MIXER**

(71) Applicant: **WHIRLPOOL CORPORATION**,
Benton Harbor, MI (US)

(72) Inventors: **Antonius K. Aditjandra**, St. Joseph,
MI (US); **Richard D. Arnold**, St.
Joseph, MI (US); **Amy Beisiegel**,
Berrien Springs, MI (US); **Lynsey A.
Howse**, St. Joseph, MI (US); **Joy
Kathleen Kempic**, Stevensville, MI
(US); **John W. McConnell**, St. Joseph,
MI (US); **Brandon Tyler Mock**, St.
Joseph, MI (US); **John Jay Myers**,
Saugatuck, MI (US); **Nicholas Hill
Schutte**, St. Joseph, MI (US); **Yifan
Wang**, Benton Harbor, MI (US); **Rex
D. Wilson**, Stevensville, MI (US)

(73) Assignee: **WHIRLPOOL CORPORATION**,
Benton Harbor, MI (US)

(**) Term: **15 Years**

(21) Appl. No.: **29/828,905**

(22) Filed: **Mar. 1, 2022**

(51) LOC (15) Cl. **31-00**
(52) U.S. Cl.
USPC **D7/379**

(57)

CLAIM

The ornamental design for a hand mixer as shown and described.

DESCRIPTION

FIG. 1 is a perspective view of a hand mixer showing the claimed design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings show portions of the hand mixer and form no part of the claimed design.

1 Claim, 7 Drawing Sheets
